UNITED STATES PATENT OFFICE.

JOHN JOSIRA MOSS, OF CHICAGO, ILLINOIS.

TELEPHONE SUPPORT.

Application filed July 24, 1922. Serial No. 577,205.

To all whom it may concern:

Be it known that I, JOHN JOSIRA Moss, a citizen of the United States, and a resident of Chicago, in the county of Cook and State of Illinois, have invented a new and useful Improvement in Telephone Supports, of which the following is a full, clear, and exact description.

My invention relates to improvements in telephone supports, and it consists in the combinations, constructions, and arrangements herein described and claimed.

An object of my invention is to provide a telephone support which may be readily secured to a wall or the like, and which has means for readily and instantly adjusting the telephone to the desired height.

A further object of my invention is to provide a device of the character described which has novel means for supporting the receiver when the latter is not disposed on the ordinary telephone hook.

A further object of my invention is to provide a device of the character described which may be folded so as to take up little room when the telephone is not disposed thereon.

A further object of my invention is to provide a device of the character described which is simple in construction, durable and efficient for the purpose intended, and which is not likely to easily get out of order.

Other objects and advantages will appear in the following specification, and the novel features of the invention will be particularly pointed out in the appended claims.

My invention is illustrated in the accompanying drawings, forming part of this application in which—

Figure 1 is a front elevation of the device, and

Figure 2 is a side elevation of the device, portions thereof being broken away.

In carrying out my invention, I provide a supporting board 1 of the shape shown in the drawing. This board may be readily attached to a wall or other supporting surface by screws or the like. The board 1 is preferably disposed at the required height so as to permit the person using the telephone to stand and readily speak into the telephone with slight inconvenience to him. A novel telephone carrying means is carried by the board 1 and is adapted to support the telephone in various positions with respect to the board, whereby people of va-

rious heights may use the same telephone without any inconvenience to them.

This means is clearly shown in the drawings and comprises a casing 2 which has integral lugs 3 through which screws 4 are disposed, these screws rigidly securing the casing to the board 1. In Figure 1 I have shown the casing as being provided with a vertically extending slot 5 in the front surface thereof. A corrugated plate 6 (see Figure 2) is disposed directly in back of the front wall 7 of the casing 2 and is secured in place by rivets 8. This plate also has a slot therein which is directly aligned with the slot 5 and is of the same dimensions.

A telephone supporting stand 9 is carried by an arm 10 which has an upwardly extending portion 11, the latter being slidably received within the slot 5. The upper end of the arm 11 is bent outwardly and is provided with lugs 12 which are adapted to be received in the corrugations of the plate 6 (see Figure 2). A plate 15 extends at right angles to the arm 10 and is rigidly secured thereto by a bolt 16. The bolt 16 extends through the base 9, the arm 10, and the plate 15. From this construction it will be apparent that the base 9 may be rotated with respect to the arm 10 and the plate 15.

A thin disc 17 is secured to the base 9 and is disposed between the base 9 and the arm 10. This disc is provided with a hinge 18 (see Figure 1), to which a hinged platform 19 is pivotally secured. This platform has lugs 20 which project beyond the hinge 18, these lugs being adapted to straddle the plate 15 or the arm 10 so as to lock the base 9 in various positions. When the platform 19 is in the position shown in Figure 2, the base 9 may be readily rotated with respect to the arm 10 and the plate 15. By swinging the platform 19 from the position shown in Figure 2 into the position shown in Figure 1, the lugs 20 are swung beneath the disc 17 and receive the arm 10 or the plate 15. When the platform is in this position, it locks the base against further rotative movement.

The lugs 12 are locked in engagement with the corrugated plate 6 by a spring pressed locking bolt 21. This bolt is threaded into an opening 22 in the arm 11 and extends through a square lug 23 of a spring clamping member 24. A fiber washer 23' is disposed on the lug 23 and has corrugations

25 therein, whereby the friction between the fiber washer and the wall 7 is greatly increased. As clearly shown in Figure 2, the plate 24 is U-shaped and the bolt 21 extends 5 through both portions or arms of the plate 24. The upper end of the plate 24 is provided with a hinge 26, to which a telephone retaining arm 27 is pivotally secured. In Figure 2 I have shown the two positions 10 into which the arm 27 may be swung. The shape of the arm 27 is clearly shown in Figure 1, and comprises two spring wire members which have a loop portion 28 therein. The loop portion is adapted to snugly receive 15 the supporting stem 29 of the telephone. It will therefore be apparent that the wire arms of the member 27 are sprung outwardly as the telephone is disposed therein. A coil spring 30 is mounted on the 20 bolt 21 and is disposed between the sides of the plate 24. The spring is adapted to move the bolt 21 outwardly so as to cause the lugs 12 to engage with the corrugations of the plate 6. The lugs 12 can be moved out of 25 engagement with one set of grooves in the plate 6 and be disposed in another set of grooves by merely forcing the base 9 up or down. In this manner, the height 30 of the telephone may be instantly adjusted to the person who is speaking. I also provide a locking bolt 31 which is secured to the arm 11 and which projects through the slot 5. A thumb nut 32 is mounted on the bolt 31 and is adapted to be 35 rotated so as to secure the arm 11 in adjusted position. When the nut 32 is tightened, the base 9 cannot be moved with respect to the board 1.

40 From the foregoing description of the various parts of the device, the operation thereof may be readily understood. The device is adapted to support a telephone in place of the ordinary desk or other article of furniture upon which the telephone is 45 usually disposed. As heretofore stated, the device is disposed at substantially the height of a person when standing so that the mouth piece of the telephone is disposed at the same level as the height of the 50 speaker. With the adjustment feature heretofore described, the telephone may be moved up or down so as to instantly position it with respect to the person talking. In this manner, the telephone is always at the desired position, whereby no 55 inconvenience is experienced by the person using the instrument. The retaining arm 27 removably holds the telephone in position and readily permits the telephone to be removed from the device when 60 the person desires to do the same. The base 9 may be rotated so as to position the hinged platform 19 in any place desired. This platform may be used for a memorandum tablet or may support the receiver 65

when the latter is not being used, as is shown in Figure 1.

The device may be folded when not in use so as to take up very little room. The plate 24 not only acts as a hinge for the retaining arm 27, but also acts as a locking washer to the bolt 21. As clearly shown in Figure 2, a portion of the plate is bent outwardly so as to engage with the sides of the bolt 21 and thus hold the latter from rotating. In 75 many instances, the locking bolt 31 is not used. This permits the base 9 to be moved so as to raise the telephone to the required elevation for the different people using the same. The spring bolt 21 is strong enough to 80 yieldingly hold the base 9 in adjusted position. The device is very simple in construction and is thoroughly efficient for the purpose intended. The device is also neat in appearance and is pleasing to the eye. 85

It should be noted that the lug 23 prevents the plate 24 and the arms 27 from rotating with respect to the casing 2, since the lug is slidably received in the slot 5, the 90 sides of the lug abutting the sides of the slot.

I claim:

1. A device of the type described comprising a base, a casing having a longitudinal slot therethrough, a corrugated metal strip in said casing adjacent to said slot, a platform slidably supported in the slot in said casing, a lug forming a part of the supporting means for said platform, a bolt set in said supporting means adjacent to said lug and extending exteriorly of said casing, and a U-shaped spring member disposed on said bolt between the head thereof and the outer wall of said casing, whereby said lug may be yieldably held into engagement with 100 said corrugated strip.

2. A device of the type described comprising a base, a casing having a longitudinal slot therethrough, a corrugated metal strip in said casing adjacent to said slot, a bracket slidably supported in the slot in said casing, a platform supported on said bracket, a lug forming a part of said bracket arranged in registration with said corrugated strip, a bolt set in said bracket adjacent to said lug and having its head portion extending exteriorly of said casing through said slot, a fiber washer on said bolt adjacent to the outer side wall of said casing, and a resilient U-shaped metal member on said bolt between said washer and the head of said bolt. 110

3. A device of the type described comprising a base, a platform adjustably carried by said base, said platform being adapted to be rotated, and a telephone receiver carrying plate pivotally secured to said platform and being adapted to lock said platform against rotation. 125

4. In a device of the character described, a bracket having radially extending por- 130

tions disposed in a horizontal plane, a platform pivotally mounted on said bracket at the center of said radially extending members, and a telephone receiver carrying plate 5 hingedly supported on said platform intermediate its length, a portion of said hingedly supported plate being fashioned to provide a pair of spaced apart lugs arranged to straddle said radially extending members 10 selectively when said plate is moved with said platform into registration with said members and hinged in a plane contiguous to said platform.

5. A device of the type described comprising a plate adapted to be secured to a vertically extending wall, a telephone platform adjustably carried by said plate, said platform adapted to be rotated, telephone receiving arms pivotally carried by said plate and being adapted to receive a telephone 15 therebetween, and a receiver carrying platform pivotally carried by said plate and being adapted to lock said telephone carrying platform against rotation. 20

JOHN JOSIRA MOSS.
